PUSH BUTTON ELECTRIC SWITCH

Norman William Stevenson, Macclesfield, England,
assignors to V. & E. Friedland Limited, Maccles-
field, England, a British company

Filed Mar. 12, 1962, Ser. No. 69,207

Claims priority, application Great Britain Sept. 13, 1961

Term of patent 14 years

(Cl. D26—13)

FIG. 1.

FIG. 2.

FIG. 3

FIGURE 1 is a front perspective view from above and one side.

FIGURE 2 is a rear perspective view from below and from the other side.

FIG. 3 is a side elevational view thereof.

My design comprises a substantially rectangular housing wherein the upper portion is covered by a square, flush-fitting, opaque casing, said casing being provided with a circular aperture through which a push button projects. The aperture is larger in diameter than the push button to permit a portion of the transparent housing to appear in the form of an illuminable ring around the push button. The uncovered lower portion of the trans-

parent structure is an illuminable rectangular section in which a name plate is to be displayed.

I claim:

The ornamental design for a push button electric switch, as shown.
